United States Patent Office.

CHARLES H. HELMS, OF POUGHKEEPSIE, NEW YORK.

Letters Patent No. 80,952, dated August 11, 1868.

IMPROVEMENT IN MACHINE FOR SCARFING LEATHER.

The Schedule referred to in these Letters Patent and making part of the same.

TO ALL WHOM IT MAY CONCERN:

Be it known that I, CHARLES H. HELMS, of Poughkeepsie, Dutchess county, and State of New York, have invented certain new and useful Improvements in Machines for Scarfing Leather for boots, shoes, and other purposes; and I do hereby declare that the following is a full description of the same.

The nature of my invention consists in combining with a horizontally-adjusted straight-edge cutter or knife, two feed-rollers, having their peripheries bevelled in opposite directions, so that the horizontally-adjusted cutter, opposed to the space between the said rollers, will form an oblique cut across the face of the leather as it passes through the said space intervening between the rollers.

But to describe my invention more particularly, I will refer to the accompanying drawings forming a part of this specification, the same letters of reference, wherever they occur, referring to like parts.

Figure 1 is a front view of the machine, showing the lower portion of the frame broken off.

Figure 2 is a vertical cut section of the same, through the line $x^1 x^2$, fig. 1.

Figure 3 is a plan view of the machine, through the line $x^3 x^4$, fig. 1.

Letter A represents a metal stand or frame, and B a shaft passing through the body of it. On the front end of this shaft is secured a cone-shaped roller, c, whose smallest diameter projects outwards. Above and parallel with the shaft B is a second shaft, D, through the frame, having on its front end another cone-shaped roller, E, whose smallest diameter projects inwards. The shaft of this roller is secured into an adjustable box, F, working up and down within a chamber, G, formed in the upper side of the frame of the machine, and having on the head of it a spiral spring, H, confined under a cap-plate, I, for the purpose of allowing the roller E to have an elastic self-adjustable pressure on the leather in passing between the rollers. To admit of this self-adjusting motion in the frame of the machine, the openings through it for the shaft D are made oblong, as shown at J.

Letter K is a horizontal adjustable cutter or knife, secured, by a set-screw, L, to a seat formed on one side of the frame of the machine, and on a straight line between the opposing edges or faces of the two rollers. The object of this is to make an oblique cut across the face of the leather passing between the rollers. This will be obvious, for the reason that the faces of the two rollers cause the leather to pass between them on a slant, and, as the edge of the cutter is perfectly horizontal, that is, touches the inner edge of the periphery of the lower roller and the outer edge of the periphery of the upper roller, it produces a cut obliquely across the face of the piece of leather, and thus produces a thin and uniform scarfing of its edges. To enable the cutter to act with a drawing-cut, its edge is made projecting from its outer point to its inner point, as shown at m and n. For the purpose of graduating the width of the scarf, an adjustable gauge, P, is secured to the frame of the machine, of such a shape and in such a position as to project between the two rollers at the entering side of them.

Letters R and S are two cog-wheels on the shafts of the rollers for communicating uniform rotary motion to them by means of any suitable crank or pulley-motion applied to the roller-shaft B.

For the purpose of causing the rollers to carry the leather firmly forward against the edge of the cutter, the roller E has its edge or periphery serrated. It will be obvious that either roller or both may be serrated, and also that the cutter will operate to make a scarf, though but one of the rollers were made tapering, and the other of uniform diameter.

Having now described my invention, I will proceed to set forth what I claim and desire to secure by Letters Patent of the United States.

I claim the combination of the stationary horizontal cutter with the rollers c and E, or either of them, having their edges or peripheries bevelled obliquely to the edge of the cutter, substantially as hereinbefore described and for the purposes set forth.

C. H. HELMS.
